Primary Examiner — Karen Kearney*Assistant Examiner* — Sharon S Oum(74) *Attorney, Agent, or Firm* — Finnegan, Henderson, Farabow, Garrett & Dunner LLP(57) **CLAIM**

The ornamental design for a display screen with graphical user interface, as shown and described.

DESCRIPTION

FIG. 1 is a front view of a first embodiment of a display screen with graphical user interface showing the new design; and,

FIG. 2 is a front view of a second embodiment of a display screen with graphical user interface showing the new design. The broken lines of uneven length show the display screen. The broken lines of even length shown in the drawings illustrate portions of the display screen with graphical user interface that form no part of the claimed design.

1 Claim, 2 Drawing Sheets
